UNITED STATES PATENT OFFICE.

GEORGE R. SHEPHERD, OF BROOKLINE, MASSACHUSETTS.

SIDE-CURTAIN CONFINER FOR VEHICLES.

1,407,091.

Specification of Letters Patent. Patented Feb. 21, 1922.

Application filed November 30, 1920. Serial No. 427,350.

To all whom it may concern:

Be it known that I, GEORGE R. SHEPHERD, a citizen of the United States, residing at Brookline, in the county of Norfolk, and 5 State of Massachusetts, have invented new and useful Improvements in Side-Curtain Confiners for Vehicles, of which the following is a specification.

This invention relates to an automobile or 10 other vehicle body, having a top or hood, the top including a side curtain, a lower corner portion of which is separably connected with a fastener member on the body. In many vehicles a vertical edge portion of said 15 curtain, above said corner portion, is more or less in the path of persons leaving the vehicle, and is consequently liable to be pressed outward, so that outward strain is exerted on the corner engaged by the fastener member on the body. Said fastener member has heretofore been rigidly attached to the body and incapable of yielding to outward strain exerted on the curtain, so 20 that such strain is liable to break or tear the curtain at the point where it is engaged by the fastener member.

My invention has for its object to obviate this liability and enable the curtain corner-engaging fastener member to yield to outward strain exerted on the curtain, and thus 25 prevent injury to the curtain by such strain.

The invention is embodied in the improvements which I will now proceed to describe and claim.

35 Of the accompanying drawings forming a part of this specification,—

Figure 1 is a side view, showing an automobile body and a top, including two side curtains, portions of which are yieldingly secured by means embodying the invention.

Figure 2 is an enlargement of a portion of Figure 1.

Figure 3 is a section on line 3—3 of Figure 2.

45 Figure 4 is a view similar to Figure 3, showing a different arrangement of parts.

Figure 5 is a side view, showing a different embodiment of the invention, and portions of the body and of a curtain, the latter being shown by dotted lines.

50 Figure 6 is a section on line 6—6 of Figure 5.

The same reference characters indicate the same parts in all of the figures.

55 In the drawings, 12 represents an automobile body having doors 13, and a top

which includes side curtains 14, 14 and 15, the body and top here shown being of well known construction, and the curtains being detachably secured to the body of any suitable separable fasteners, including members carried by the body, and members carried by the curtains. The members carried by the body are usually stud members, and those carried by the curtains are usually 65 socket members, adapted to receive and separably engage the stud members.

The forward vertical edges of the curtains 14 are usually in alinement with the rear vertical edges of the doorways, the relative 70 arrangement of the curtains and doorways being such that the forward vertical edges of the curtains 14 are to some extent in the path of a passenger leaving the vehicle, so that the passenger is liable, in leaving the 75 vehicle, to press outward against the forward edge portion of a curtain 14. The strain caused by this pressure is resisted at the lower forward corner of the curtain by the fastener member on the body engaged 80 with said corner, so that, when said fastener member is rigidly attached to the body as usual, the curtain is liable to be torn at its lower forward corner portion. To prevent this liability, I provide a resilient connection 85 between the body and the fastener member thereon which engages the lower front corner of the curtain, said connection normally holding the said fastener member, and the curtain corner engaged thereby, in a 90 predetermined position close to the body, and permitting the fastener member and the curtain corner to yield outwardly to strain exerted on the forward portion of the curtain by a person leaving the vehicle. 95

In illustrating the invention I show only the said yieldingly connected fastener members. It will be understood that other portions of the curtains are detachably secured, as usual, by fastener members rigidly attached to the body, and engaging complementary fastener members on the curtains, so that the curtains are detachable from the top and body.

105 In each of the figures of the drawings, 17 designates a fastener member carried by the body and connected therewith by resilient means, in accordance with my invention. Said member, as here shown, is a stud member, adapted to separably engage a socket 110 member 18 on the lower front corner portion of a curtain 14.

In the embodiment of the invention shown by Figures 2 and 3, I provide the means next described for connecting the member 17 with the body. 19 represents a holder formed as a tube and rigidly secured to the body by being inserted in a socket formed in the body. Said holder has an abutment 20 and a guide 21, at its upper end. A helical spring 22 is seated at one end on said abutment, its opposite end being free and provided with a cap 23 which is movable with the spring. The member 17 is provided with a shank 24, and with a flexible connection or tether 25, attached to the shank and to the cap 23, and passing through the guide 21. When a person leaving the vehicle presses against the forward edge portion of the curtain engaged with the member 17, said curtain portion and member yield, or are displaced outward from the body, as shown by dotted lines in Figure 3, the spring 22 being at the same time compressed. When pressure is removed from the curtain, the spring expands and draws the member 17 and the curtain back to their predetermined normal position shown by full lines.

Each embodiment of the invention constitutes a curtain confiner adapted to detachably connect a side curtain with a fixed portion of a vehicle, and to yieldingly restrain the curtain in its operative relation to said portion, so that the curtain may yield to displacing pressure from within the vehicle. In each embodiment there is an anchoring means, such as that provided by the holder 19 or 19a (Figures 3 and 4), or by the clamping plates 31 and 32 and screw 33, (Figures 5 and 6). In each embodiment there is a spring take-up connection between the anchoring means and a curtain-engaging fastener member 17, such as that provided by the spring 22 and tether 25, or that provided by the wire portions 28, 29 and 30, the take-up connection in each case having resilient means whereby the fastener member 17 is normally maintained at a predetermined distance from the anchoring means, and is permitted to be abnormally separated from the latter.

50 The structure shown by Figures 2 and 3 is preferred, when the confiner of my invention is applied to the body while the latter is in process of construction.

Figure 4 shows a similar structure, adapted for application to a vehicle already in use, the tubular guide 19a being provided with ears 26, bearing on the exterior of the body 12, and attached thereto by screws 27, the operation being the same as that of the structure first described.

In Figures 5 and 6 I show as the resilient portion of the connecting means, a length of resilient wire bent to form helical spring portions 28, a looped arm 29 connecting the outer ends of the spring portions and en-

gaged with the shank 24, and a looped arm 30 connecting the opposite ends of the spring portions. The holder portion of the connecting means includes annular clamping plates 31 and 32, between which the looped arm 30 is interposed, and a screw 33 securing said plates to the body 12. The arm portion 29 and spring portions 28 permit the displacement of the member 17 and the curtain portion engaged therewith, and cause the return of said member and curtain portion to their normal position.

As implied in the foregoing description and in the following claims, I am not limited to the specific mechanism of the embodiments of my improvements shown by the drawings, except as otherwise required in certain of the more limited claims.

I claim:

1. A side curtain confiner for vehicles, comprising a fastener member engageable with a curtain, anchoring means attachable to a portion of a vehicle, and a spring take-up connection between the anchoring means and the fastener member, said connection having means for normally holding the fastener member at a predetermined minimum distance from the anchoring means, and for permitting outward displacement of the fastener member. 95

2. A side curtain confiner for vehicles, comprising a fastener member engageable with a curtain, an anchoring member attachable to a portion of a vehicle and provided with a spring abutment and with a guide, and a spring take-up connection between the anchoring member and the fastener member, said connection including a spring seated on said abutment, and a flexible tether engaged with the spring and with the fastener member and passing through said guide, the arrangement being such that the spring and tether normally hold the fastener member at a predetermined minimum distance from the guide portion of the anchoring member, and permit outward displacement of the fastener member. 105 110

3. A side curtain confiner for vehicles, comprising a stud fastener member engageable with a socket fastener member on a curtain, anchoring means attachable to a portion of a vehicle, and a spring take-up connection between the anchoring means and the stud member, said connection having means for normally holding the stud member at a predetermined minimum distance from the anchoring means, and for permitting outward displacement of the fastener member. 115 120

4. A vehicle body having a yielding curtain confiner, arranged to confine a portion of a side curtain beside a doorway, and comprising a fastener member engageable with said curtain portion, anchoring means fixed to the body beside said doorway, and a 125 130

spring take-up connection between the anchoring means and the fastener member, having means whereby the said member is normally maintained at a predetermined location on the body, and is permitted to be abnormally separated from said location, by outward pressure on the inner side of the curtain.

5. In combination, a vehicle body having a side curtain, and extensible means for detachably fastening said curtain and retaining the same yieldingly toward said body.

In testimony whereof I have affixed my signature.

GEORGE R. SHEPHERD.
